MAGNETO

Heinrich Bischoff, Korntal, Germany, assignor
to Robert Bosch Gesellschaft mit beschränk-
ter Haftung, Stuttgart, Germany

Application September 9, 1935, Serial No. 39,872
In Germany September 18, 1934

10 Claims. (Cl. 171—209)

The present invention relates to magnetos which are provided with a distributor for two separate ignition circuits driven by a transmission drive and more particularly to those having a stationary armature and magnet system, and a rotating conducting member.

In order to provide a simple compact magneto of the type just described and to obtain a minimum lateral loading of the distributor and its drive, according to the invention the distributor and its transmission gearing are arranged substantially coaxially with the magneto rotor.

An example of construction of the invention is shown in the accompanying drawings, in 15 which:—

Figure 1 shows a twin magneto in longitudinal section on the line I—I of Fig. 2,

Figure 2 is a sectional view on the line II—II of Fig. 1, and

Figure 3 is a longitudinal sectional view, similar 20 to Fig. 1, taken on the line 3—3 of Fig. 2.

The magneto consists of two armatures *a* and two magnets *b* which are combined to form a stationary system, and a rotating flux conducting 25 member *c* which is positioned on the driving shaft *d* of the magneto.

The shaft projects beyond the conducting member and is mounted in bearings *v* near its end. Surrounding this portion of the shaft, is arranged 30 a distributing device *e* and an interrupter, the driving cams of which are positioned on the shaft. The distributor consists of two rotating distributor elements *g* and *g*₁, which are mounted axially side by side on a tube *h*, which is fixed to the 35 distributor casing *i*, and whose axis is eccentric to the axis of the magneto shaft *d*. The distributor elements are fixed on a rotatable bush *k*. At the inner end of the bush a gear-wheel *o* with internal teeth is secured by flanging over the 40 edge of the bush, which gear-wheel meshes with a toothed wheel *p* having external teeth, which is secured to the magneto shaft *d*. The distributor elements *g* and *g*₁ have slip-rings *q*, to which the high tension magneto current of the armature 45 *a* is led by connections *u*. Electrodes *r* are connected to the slip-rings, and conduct the magneto current to the electrodes *s* of a stationary distributor disc *t*.

I declare that what I claim is:

60 1. A magneto comprising a stationary armature, a stationary magnet system, a rotary magneto shaft, a flux conducting member connected to said shaft, two rotatable distributor elements for separate ignition circuits arranged axially side by side and eccentrically of said shaft, means

independent of and surrounding a portion of said magneto shaft for mounting said distributor elements for rotation about said shaft, an internally toothed ring connected to said distributor elements and a gear-wheel mounted on the magneto shaft and meshing with said internally toothed ring for driving said distributor elements.

2. In a magneto having a rotating magneto shaft, two rotatable distributor elements for separate ignition circuits arranged axially side by side and eccentrically of said shaft, a stationary tube arranged eccentrically of and surrounding said shaft and rotatably mounting said rotatable distributor elements, an internally toothed ring connected to said distributor elements and a gear-wheel mounted on the magneto shaft and meshing with said internally toothed ring for driving said distributor elements.

3. In a magneto having a rotating magneto shaft, two rotatable distributor elements for separate ignition circuits arranged axially side by side and eccentrically of said shaft, a stationary tube arranged eccentrically of and surrounding said shaft, a rotatable bush mounted on said tube and to which said distributor elements are fastened, an internally toothed ring connected to said bush and a gear-wheel mounted on the magneto shaft and meshing with said internally toothed ring for driving said distributor elements.

4. In a magneto having a rotating magneto shaft, a stationary tube arranged eccentrically of and around said shaft, a rotatable bush borne on said tube, two rotatable distributor elements for separate ignition circuits arranged axially side by side on said bush and eccentrically of said shaft, an internally toothed ring secured to said bush by flanging of the bush and a gear-wheel on the shaft meshing with said ring for driving said distributor elements.

5. In a magneto having a rotatable magneto shaft, a rotary member carried by said shaft, a stationary hollow shaft surrounding one end of said rotatable magneto shaft and arranged eccentrically thereof, a distributor rotatably mounted on said hollow shaft, and means for drivably connecting said magneto shaft and said distributor.

6. In a magneto having a rotatable magneto shaft, a rotary member carried by said shaft, a stationary hollow shaft surrounding one end of said rotatable magneto shaft and arranged eccentrically thereof, a distributor rotatably mounted on said hollow shaft, and means for

drivably connecting said magneto shaft and said distributor comprising a gear wheel mounted on the magneto shaft and meshing with an internally toothed ring carried by said hollow shaft.

5. 7. In a magneto, a casing, a rotatable magneto shaft rotatably mounted by said casing, a rotary member carried by said shaft, a stationary hollow shaft mounted at one end by said casing, said hollow shaft being arranged about and eccentrically of said rotatable magneto shaft, a distributor rotatably mounted on said hollow shaft, and means for drivably connecting said magneto shaft and said distributor.

8. In a magneto, a casing, a rotating magneto shaft rotatably mounted by said casing, a rotary member carried by said shaft, said casing including an integral hollow extension which surrounds a portion of said magneto shaft and is arranged eccentrically thereof, a distributor rotatably mounted on said hollow extension, and

means for drivably and rotatably connecting said magneto shaft and said distributor.

9. A magneto comprising a stationary armature, a stationary magnet system, a rotatable shaft, a rotatable flux conducting member carried by said shaft, a tube arranged about said shaft, a distributor for two separate ignition circuits rotatably mounted on said tube, and transmission gearing for said distributor comprising a gear wheel mounted on said shaft and meshing with an internally toothed ring connected to said distributor. 5

10. In a magneto, a rotatable magneto shaft, an inductor carried by said shaft, a rotary distributor, means independent of and surrounding a portion of said shaft for mounting said distributor for rotation about said shaft, and rotatable driving means connecting said shaft and said distributor. 10 15
